DESIGN FOR A HAND MIRROR

Harry A. Werfel, Caldwell, N. J.

Application September 18, 1935, Serial No. 58,610

Term of patent 3½ years

To all whom it may concern:

Be it known that I, Harry A. Werfel, a citizen of the United States, residing at Caldwell, in the county of Essex and State of New Jersey, have invented a new, original, and ornamental Design for Hand Mirrors, of which the following is a specification, reference being had to the accompanying drawing, forming part thereof.

In said drawing, Fig. 1 is a front face view, Fig. 2 is a rear face view, and Fig. 3 is an edge elevation of a hand mirror, showing my new design.

I claim:

The ornamental design for a hand mirror, as shown.

HARRY A. WERFEL.
